**COMBINED STANDARD AND INTERNALLY
ILLUMINABLE RESIDENTIAL SIGN**

Charles B. Parker, Lubbock, Tex.

Application January 6, 1959, Serial No. 54,054

Term of patent 14 years

(Cl. D1—12)

Fig. 1 is a front elevational view of a combined standard and internally illuminable residential sign showing my new design, the rear, not shown, being substantially the same as the front shown.

Fig. 2 is a top plan view thereof.

Fig. 3 is a fragmentary right side elevational view thereof.

I claim:

The ornamental design for a combined standard and internally illuminable residential sign, as shown and described.
